Attorney.

UNITED STATES PATENT OFFICE.

WILLIAM AUGUST HOFFMAN, OF ST. LOUIS, MISSOURI, ASSIGNOR TO JOHNS-MANVILLE INCORPORATED, A CORPORATION OF NEW YORK.

FORM FOR MOLDING MONOLITHIC BAFFLE-WALLS FOR WATER-TUBE BOILERS AND PROCESS OF MAKING THE SAME.

1,377,774.

Specification of Letters Patent. Patented May 10, 1921.

Application filed January 13, 1920, Serial No. 351,169. Renewed October 12, 1920. Serial No. 416,511.

To all whom it may concern:

Be it known that I, WILLIAM AUGUST HOFFMAN, a citizen of the United States of America, residing at St. Louis, State of Missouri, have invented certain new and useful Improvements in Forms for Molding Monolithic Baffle-Walls for Water-Tube Boilers and Processes of Making the Same, of which the following is a specification.

10 My invention relates to water tube boilers in general and more specifically consists of a form for molding the monolithic baffle walls now employed in many types of such boilers. As the tubes in such boilers are massed together in large numbers and located closely together to save space, it is a somewhat difficult matter to get the necessary forms in and around the tubes so that the plastic mixture for forming such desired baffle walls can be 15 poured into the forms and allowed to set 20 around the tubes.

25 My invention supplies an inexpensive, convenient apparatus and method for doing this and the best form of such apparatus at present known to me embodying the invention is illustrated in the accompanying sheet of drawings in which—

30 Figure 1 is a vertical, longitudinal section of a well known type of water tube boiler showing the location of the baffle walls;

35 Fig. 2, is a front view with parts broken away of one of the built-up partitions forming the molding for the baffle wall constructed in accordance with my invention, the boiler tubes being shown in section,

40 Fig. 3, is a cross section on the line 3—3, of Fig. 2, and shows the two partitions or form walls and the plastic material for the baffle walls poured into said form.

45 Fig. 4, is a detail perspective view of one of the split washers used in my invention, and

50 Fig. 5, is a similar view of the notched stick used for inserting the split washers in place.

Throughout the drawings like reference figures indicate like parts.

1, represents the boiler generally, having the closely massed set of water tubes, 2. The furnace or combustion chamber for the boiler has the usual bridge walls 3, 3, so as to force the hot gases to pass between the tubes. The action of the bridge walls is

further increased by the baffle walls 4, 4, 55 which are built upon and serve as extensions of them. As shown by the arrows in Fig. 1, these baffle walls cause the hot gases to pass back and forth across all of the tubes so that even heating of them is assured. 60

The spaces between the tubes 2, are obviously too small to permit the convenient installation of separate bricks with which to build up the baffle walls. It is therefore becoming customary to mold these baffle walls 65 4, 4, in position. To do this, it is necessary to build a form in and around the tubes and this, of course, consists of two partitions arranged parallel one to another, leaving a space between them into which fire-proof cement or other plastic material may be poured and then allowed to set around the tubes. According to my invention these partitions are built up in the following manner: 70 75

A series of strips of wood or other stiff material 6—6, of such thickness as is consistent with their being slipped in diagonally between the boiler tubes, are inserted between each two diagonal rows of tubes and 80 crossed in position as shown in Fig. 2. The tubes 2, being usually staggered regularly as shown, one set of strips 6, 6, are inserted slanting to the right and another set 7, 7, are inserted slanting to the left and those abutting against one of the furnace side walls as 5, 85 are beveled off at the ends as shown in Fig. 2.

This forms a lattice work surrounding the boiler tubes, but obviously large open spaces 90 are left between the tubes and the strips forming the lattice. To cover these openings, I employ a plurality of spring washers 8—8, of any suitable material which are split as shown in Fig. 4, and which can be snapped 95 over the boiler tubes, one washer on each tube, to coöperate with the lattice work and form a substantially imperforate partition as indicated in Fig. 2.

The preferred method of building up these partitions is to first insert the lattice strips of one inclination as 6, 6, and then to insert the split washers 8, 8, by placing them one at a time in the end of a split stick 10, which is inserted between the tubes and then turned 105 so that the washer snaps over the particular tube for which it is intended, and then after all the tubes have been equipped with wash-

ers in this manner, to insert the second set of lattice strips 7, 7, which are inclined to the left. The two sets of strips are then pushed closely together pressing the washers between them and a substantially imperforate partition is thereby formed.

To hold the parts firmly in position, the upper and lower ends of the lattice strips may be nailed or otherwise firmly fastened 10 to horizontal strips 9, 9, as clearly shown in Figs. 2 and 3. Two such partitions having been formed about the tubes at a proper distance apart, as shown in Fig. 3, the plastic material 11, is then poured in and allowed to 15 set. This forms a monolithic baffle wall, as shown in Fig. 1. If desired, the lattice strips may then be unfastened one from another and withdrawn for use again and the split washers may also be sprung off of the tubes 20 if the operation of so salvaging them is not more costly than it would be to supply new ones for the next job. On the other hand, of course, the parts may all be left in position and burned off when the boiler furnace goes 25 into operation.

Having described my invention, I claim:

1. A form for molding a monolithic baffle wall around a set of regularly spaced boiler tubes which comprises in combination a series 30 of strips of stiff material inserted diagonally between the tubes and arranged all in substantially the same plane, a series of washers placed one around each tube adjacent to the strips, and a second series of strips 35 inserted between the tubes at an inclination opposite to that of the first set, adjacent to and on the opposite side of the washers.

2. A structure such as set forth in claim 1 combined with horizontal top and bottom strips to which the ends of the diagonally 40 arranged strips are fastened.

3. A form for molding a monolithic baffle wall around a set of staggered boiler tubes which comprises in combination two properly spaced partitions extending crosswise 45 of the tubes, each partition being composed of a lattice work of narrow, stiff strips inserted between the tubes, and a washer around each tube adjacent each lattice of a diameter sufficient to cover the spaces left between the tubes and strips forming the lattice.

4. The method of building a monolithic baffle wall about and across a set of staggered boiler tubes which comprises the following 55 steps: first inserting a series of stiff strips diagonally between the tubes, all the strips being in substantially the same plane; second, inserting a series of split washers and springing one around each tube adjacent to 60 the set of strips; third, inserting a second set of strips on the other side of the washers oppositely inclined to those of the first set; fourth, building another similar form around the tubes at a distance from the first, 65 and fifth, pouring a plastic mass of high temperature cement between the two sets of assembled strips and washers so installed, and allowing the same to set.

WILLIAM AUGUST HOFFMAN.
